UNITED STATES PATENT OFFICE.

WILLIAM E. LUHMAN, OF PORT CHESTER, NEW YORK.

FIRE-EXTINGUISHER.

No. 880,551.

Specification of Letters Patent.

Patented March 3, 1908.

Application filed April 11, 1907. Serial No. 367,490.

To all whom it may concern:

Be it known that I, WILLIAM E. LUHMAN, a citizen of the United States, residing in Port Chester, in the county of Westchester 5 and State of New York, have invented certain new and useful Improvements in Fire-Extinguishers, of which the following is a specification.

This invention relates to an improved 10 fire-extinguisher which is charged with water and discharged with a carbonate solution and which is provided with an acid-bottle the contents of which are supplied at the time the extinguisher is required for use.

15 In fire-extinguishers of this class heretofore in use it was customary to break the bottle containing the sulfuric or other acid by means of pressure applied to the bottle. This required the replacing of the bottle after 20 every use of the fire-extinguisher. This was annoying, inconvenient and expensive.

25 The object of this invention is to dispense with the breaking of the glass bottle so that the apparatus can be charged immediately after use without requiring a new bottle; and for this purpose the invention consists 30 in a fire-extinguisher embodying the novel features and combinations of parts to be hereinafter described and pointed out in the claims.

In the accompanying drawings, Figure 1 35 represents a side-elevation of my improved fire-extinguisher, Fig. 2 is a vertical central section of the same, Fig. 3 is a detail perspective view of the frame for supporting the acid-bottle detached from the extinguisher, Fig. 4 is a vertical transverse section through the acid-bottle, and its holder on line 4, 4, Fig. 2, and Figs. 5 and 6 are perspective 40 views respectively of the glass holder for the acid-bottle and of the acid-bottle itself.

Similar letters of reference indicate corresponding parts throughout the several figures.

45 Referring to the drawings, *a* represents a cylindrical receiver which is preferably made of copper or other suitable sheet-metal, and which is provided with a tightly riveted bottom and with an opening in its top to which a 50 cover *b*, provided with a hinged handle *b*, is secured. On a recessed interior shoulder *a* on the upper part of the receiver *a* is supported the supporting-ring *d* of a frame *d* for supporting the acid-bottle. The frame *d* is provided with two downwardly-extending hang- 55 ers *d*, of which the left-hand one is provided

with a disk *d* provided with a rim *d* in which the acid-bottle *f* and its inclosing shell *f* are supported. At the lower part of the rim is a shoulder *d*. The right-hand hanger has a 60 circular rim *d* and a shoulder *d* at its lower part, the shoulders *d* and *d* serving for supporting the inclosing shell *f* which is split at its lower part, as shown at *f*, the edges of the 65 split portion resting on the edges of the shoulders *d*, *d* so as to prevent the turning of the shell *f* when the acid-bottle is turned on its axis. The shell *f* is preferably of glass. The acid-bottle is made of cylindrical 70 shape and closed at the ends and provided with an opening *f* through which it is filled with a suitable acid. The right-hand end of the acid-bottle is provided with an oblong boss or projection *f* which is made integral therewith and which is engaged by the recessed end of a key *k*, the stud-shaft of which is connected with an interior rotatable portion of a disk-shaped valve *v* which is provided with a gudgeon in line with the stud-shaft that passes through an inclosing casing 80 *v*. To the gudgeon is applied a handle *h* which abuts against stop-pins *h*, *h* attached to the exterior head of the casing. The casing is provided at the upper end with a nipple *n* to which a hose *n* having a nozzle *n* is 85 applied. The casing of the valve *v* is attached to the upper part of the receiver *a* and provided with an opening *o* at the inner wall or head of the same. The valve *v* is provided with an interior curved channel *c* 90 which is moved through an angle of 180° when the handle *h* is moved from contact with the upper stop-pin *h* into contact with the lower stop-pin *h*, so that communication between the interior of the receiver and the 95 hose *n* is established.

For charging my improved fire-extinguisher the receiver is opened and the frame with the acid-bottle removed. The acid-bottle is then removed from its split shell, 100 filled with acid and inserted, with the discharge-opening *f* at the upper part, into the glass shell *f*, the latter fitting tightly around the acid-bottle and thereby closing it. When placing the holder for the acid-bottle in position at the upper part of the receiver, the same is passed through the opening until its upper part rests on the shoulder in the upper part of the receiver. In this position the boss *f* of the acid-bottle passes into the recessed end of the key *k*, which latter is then 105 in vertical position. After the acid-bottle 110

and holder are inserted the receiver is filled nearly up to a level with the discharge-valve and acid-bottle with water in which is dissolved, preferably up to the saturation point, 5 a carbonate or other salt, which, when the acid is discharged, produces a reaction so as to set the carbonic acid or other gas free sufficiently to force the water from the receiver through the nozzle to the point where the 10 fire is to be extinguished.

Whenever it is necessary to set the extinguisher into action the handle h is moved through an angle of 180° until it is arrested by the lower stop-pin h^2 . This turns the 15 acid-bottle on its axis to a corresponding angle, so that its opening is located on the surrounding shell at the lower open part of the holder or shell and discharges freely the contents into the water in the receiver. By 20 shaking the receiver the mixture takes place quickly and the gas generated creates a sufficient pressure in the upper part of the receiver for forcing the water through the now opened valve into the hose and through the 25 hose and nozzle.

When all the water is discharged the receiver is opened again by removing the cover, the holder for the acid-bottle removed and the latter charged with acid. The receiver 30 is then recharged with a liquid saturated with a gas generated by carbonic or other acid, after which the acid-bottle is replaced in position and the cover tightly closed on the same, the holder being supported on the shoulder 35 by its contact with the cover b . Before the holder is dropped into position the operating handle is returned into upper position against contact with the upper stop-pin h^1 by which the recess of the key k is placed in line with 40 the boss of the acid-bottle, so that the same is placed in position in the recess, while the valve is moved into closed position so as to prevent any escape of gas. When the extinguisher is again required for use the same 45 operation of opening the valve and discharging the contents of the acid-bottle is repeated.

My improved fire-extinguisher has the following advantages: First, that the acid-bottle, not being broken as heretofore, can be used again after each use of the extinguisher; 50 second, that the operation of the extinguisher is easily comprehended, consisting merely in the turning of the valve-lever from one position to the other and back again; and, third,

that the recharging can be accomplished by any one with great facility.

Having thus described my invention, I claim as new and desire to secure by Letters Patent:

1. In a fire-extinguisher, the combination of a receiver, an acid-bottle mounted therein to turn on its axis and thereby discharge its contents, an outlet-valve for the receiver, means for operating said valve, and a direct 60 positive connection between said bottle and said outlet-valve whereby they are turned simultaneously.

2. In a fire-extinguisher, the combination of a receiver, an acid-bottle rotatably supported therein, a rotary outlet-valve for the receiver, means for operating said valve, and a key connecting the valve with the acid-bottle. 70

3. In a fire-extinguisher, the combination of a receiver, an acid-bottle rotatably and removably mounted therein and having a boss at one end, a rotary outlet-valve for the receiver, means for operating the same, and a key extending from the body of said valve 75 and engaging said boss.

4. In a fire-extinguisher, the combination of a bottle-supporting frame, a shell fixed in said frame and having a split lower portion, and a bottle mounted in said shell to turn 80 therein and having an outlet to register with said split portion.

5. The combination, with the receiver, of a frame supported therein, a shell fixed in said frame but freely removable therefrom, an acid-bottle mounted to turn in said shell, and means operable from the exterior of the receiver for turning said bottle. 90

6. The combination, with the receiver, of a frame mounted therein, circular rims carried 95 at each end of said frame and provided with stops, a cylindrical shell supported in said rims and having a split portion fitting over said stops, an acid-bottle mounted to turn in said shell and having an opening to register 100 with said split portion, and means for turning said acid-bottle.

In testimony, that I claim the foregoing as my invention, I have signed my name in presence of two subscribing witnesses.

WILLIAM E. LUHMAN.
